UNITED STATES PATENT OFFICE

WILLIAM J. BRADDOCK, GEORGE BRUHN, AND CHARLES W. HALLER, OF WHEELING,
WEST VIRGINIA, ASSIGNS TO WHEELING BRONZE CASTING COMPANY, A COR-
PORATION OF WEST VIRGINIA.

PICKLING APPARATUS

Application filed September 18, 1931. Serial No. 563,576.

The invention relates to pickling apparatus; that is, to apparatus for the pickling of rods, bars, tubes, and the like.

be employed in the manner indicated in Fig. I of the drawings.

The object of the invention is to provide
5 apparatus of simplified and economical structure which is adapted to move a group of bars or the like into and out of a pickling bath, and, during the operation, to effect agitation of such group.

10 A further object of the invention is to provide apparatus of the nature mentioned, in which the bars of the group are shifted relatively to each other, to the end that all surfaces of the bars will be equally and uniformly subjected to the action of the bath, whereby pickling efficiency will be obtained in largest measure.

20 A still further object of the invention is to provide pickling apparatus in which a group of bars is adapted to rest upon stationary supports within a bath of pickling fluid, and periodically to be lifted therefrom, by means of movable supports, whereby the group of bars is agitated, raised from the pickling bath, and returned to a position upon the stationary supports.

In the accompanying drawings Fig. I is a plan view of our pickling apparatus; Fig. II is a view in cross section of the same, taken on the plane II-II of Fig. I; Fig. III is a view in cross section, taken on the plane III-III of Fig. I; and Fig. IV is an isometric view of a detail in structure.

35 In the embodiment of the invention shown in the accompanying drawings, two pickling tanks 1 and 2 are arranged side by side, and at an interval from one another. Each tank contains a bath 3 (cf. Fig. II) of pickling fluid. Conveniently the tanks are rectangular in form; the tanks rest upon a plurality of sleepers 4, and on the outer side of each tank a standard 5 is supported at its base on each sleeper. Between the tanks a standard 40 45 6 is supported on each sleeper. In this case, we show relatively short tanks and have found that two sleepers with their associated standards 4 and 5 are sufficient to the end in view; however, in longer tanks, additional sleepers with their associated standards may

Within each tank there is suspended a series of flexible cradles; in this case we show two flexible cradles in each tank; conveniently, the cradles each comprise a length of chain 7, formed of acid-resisting metal. The chains 7 terminate at each of their ends in a specialized device 8, which device 8, as shown in Fig. IV, comprises a head 8a, a shank 8b, and a foot 8c. The foot is provided with one or more eyelets 8d, in which the end link of the associated chain is secured (cf. Fig. II). Secured to the top of each standard 5 is a fixture 9 which includes in structure an upwardly-extending, bifurcated portion 10. Revolvably mounted in the standards 6 is a shaft 11, to which there is secured a pair of twin-lever members 12. The outer ends of the lever elements of each of the members 12 is provided with a bifurcated portion 13, comparable with the portions 10 of fixtures 9. As is manifest in Fig. I, the chains 7 are secured to the several opposed pairs of the bifurcated elements 10, 13; that is to say, the shanks 8b of the devices 8 are disposed in the bifurcations of the elements 10, 13, and the heads 8a of devices 8 lie outwardly of the bifurcations with respect to the tank (1 or 2) with which they are associated. Accordingly, the chains 7 each form a catenary loop within one or the other of the pair of tanks 1, 2. As will presently appear, these chains 7 provide movable supports for the material to be pickled in the tanks.

In the standards 6, and conveniently below the shaft 11, there is revolvably trunnioned a shaft 14. The left-hand end of shaft 14 (cf. Fig. I) extends from between the tanks a sufficient distance to permit driving connections to be made to a source of power. Conveniently, such source of power or motion comprises a motor 15, connected to the shaft 14, by means of pinion 16 and gear 17. The right-hand end of shaft 14 extends from between the tanks, and a pitman 18 is secured thereto, while to the similarly extending end of shaft 11, there is secured an arm 19. A link 20 pivotally interconnects the pitman 18 with the arm 19, so that continuous rotation

of the shaft 14 is effective to oscillate the shaft 11 through a fractional part of a revolution. The oscillation of shaft 11 in one direction of rotation swings the twin-lever members 12 through such angular range of movement that the loops of the chains 7 in tank 2 will be progressively lowered, while the loops of the chains 7 in tank 1 are correspondingly raised. Conversely, during the oscillation of the shaft 11 and twin-levers 12 in the opposite direction, the loops of the chains within tank 1 will be progressively lowered, while the loops in tank 2 are correspondingly raised. In Fig. III, one extreme of an oscillation of the twin-levers 12 is indicated; here the loops 7 are at the top of their range of movement, while the loops in tank 1 are at the bottom of their range of movement. Continued rotation of the shaft 14 will cause the linkage 18, 19, and 20 to effect a turning of the shaft 11 and twin-lever members 12 to the opposite end of their oscillation, whereby the chains in tank 1 will provide elevated loops, while the chains in tank 2 will form lowered loops. So, continuous rotation of shaft 14 effects an oscillatory action of the twin-lever members 12, and an alternate raising and lowering of the loops formed by chains 7.

Within each tank (1, 2) there is arranged a plurality of stationary supports 21, and for reasons which will presently be perceived, the tops of these stationary supports comprise a series of faces 21a which are arranged angularly to one another.

In the operation of our apparatus, a group G of bars, or like material to be pickled, is placed in tank 1, and a group B of material to be pickled is placed within tank 2. Advantageously, the apparatus is brought to neutral position—that is, to the position indicated in Fig. II—before the groups of material G and B are placed in the tanks. When the groups G and B have been placed on the chains 7 in their respective tanks, the motor 15 is energized, and oscillatory motion is imparted to the shaft 11 and to the twin-lever members 12. This oscillation of the members 12 alternately causes the loops in chains 7 of one tank, together with their burden of bars (B or G), to rise, while the loops in chains 7 of the other tank, together with their burden, are lowered. The group of bars in one tank is raised from the bath of pickling fluid 3, while the group of bars in the other tank is being lowered into its bath. It will be perceived that the group of bars G tends to counterbalance the group B—so, a minimum of power is required to actuate the apparatus, and the operation of the apparatus is smooth, not jerky nor strained.

The alternate raising and lowering of the loops imparts to the bars carried thereby a rolling motion so that their positions with respect to each other are changed. This agita-

tion and rolling of the bars of each group is desirable, in that it tends to remove any scale present upon the surface of the bars and permits the pickling fluid to come into contact with all surfaces of the bars, thus insuring uniform pickling.

It is important to note that, when the respective chains 7 lower their groups of bars into the pickling bath, they deposit the group upon the stationary supports 21. As has been mentioned, the tops of the supports 21 comprise a plurality of angularly arranged faces 21a, so that, when the group of bars drop upon these stationary supports, the members of the group are distributed over the angular faces 21a, in the manner indicated in the right-hand portion of Fig. III. Thus, additional agitation and shifting of the members of the group are obtained when the group of bars reaches the end of its downward movement into the bath of pickling fluid. Manifestly, when, during the oscillations of the shaft 11 and members 12, the loops in chains 7 are raised, the distributed group of bars (B) will be gathered up into the bights of the chains. It will be understood that the chains 7 constitute flexible, movable supports for the material to be pickled, and that the elements 21 comprise stationary supports which co-operate with the movable supports. In combining such movable supports with stationary supports, in the manner described, we have found that the pickling efficiency is very much increased, and that the time required to pickle a group of bars or tubes is remarkably lessened.

We claim as our invention:

1. In pickling apparatus, the combination of a tank including a bath of pickling fluid, a series of flexible chains hanging in catenary loops for supporting in said tank a group of material to be pickled, a series of stationary supports in said bath, and means for alternately lowering and raising the loops in said chains, whereby said group of material is alternately deposited upon said stationary supports and lifted therefrom.

2. In pickling apparatus, the combination of a tank including a bath of pickling fluid, a series of flexible chains, means for supporting one end of each chain in fixed position, movable means for supporting the other end of each chain of the series, whereby are formed in said chains catenary loops, stationary supports in said bath, said movable means being operable to lower and raise said loops alternately for effecting alternate lowering and raising of thereby-carried material with respect to said supports.

3. In combination with a tank containing a bath of pickling fluid, a set of supports for the material to be pickled, a second set of supports which second set of supports comprises flexible loops, and means for effecting an alternate raising and lowering of said

loops, whereby said material is periodically lifted from said first-mentioned supports and agitated and returned to rest thereon.

4. In combination with a tank containing a bath of pickling fluid, a set of supports for the material to be pickled, a plurality of loops, and means for alternately shifting the plurality of loops first in one direction and then in another, whereby said material is periodically lifted from said supports and agitated and returned to rest thereon.

5. In combination with a tank containing a bath of pickling fluid, stationary supports extending transversely of the tank for the support of the material to be pickled, together with movable means for gathering into a group the material resting upon said stationary supports, and means for driving said movable means whereby the so-gathered group of material is lifted from the supports, agitated, and returned to a spread position upon said supports.

6. The method of pickling a group of bars which comprises a repetition of the steps of spreading said group of bars transversely of a pickling bath, gathering in the so-spread bars and raising them as a group through the bath, thereby effecting agitation and shifting of the bars of the group, and then lowering the group and again effecting a spreading of the group transversely of the bath.

In testimony whereof we have hereunto set our hands.
